UNITED STATES PATENT OFFICE

153,936

DESIGN FOR A MOBILE RACE CONTROL GATE

John S. Goodwin, Whittier, Calif., assignor to
Globe Oil Tools Company, Los Nietos, Calif., a
corporation of California

Application January 19, 1948, Serial No. 143,866

Term of patent 14 years

(Cl. D14—3)

To all whom it may concern:

Be it known that I, John S. Goodwin, a citizen of the United States, residing in the city of Whittier, county of Los Angeles, and State of California, have invented a new, original, and ornamental Design for a Mobile Race Control Gate, of which the following is a specification, reference being had to the accompanying drawing, forming a part thereof.

Fig. 1 is a perspective view of the mobile race control gate, showing my new design, taken from one side and end thereof, and Fig. 2 is a perspective view of the gate, taken from the other side and other end thereof.

I claim:

The ornamental design for a mobile race control gate, as shown.

JOHN S. GOODWIN.
